UNITED STATES PATENT OFFICE

OSCAR L. LAWSON, OF LYNN, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY

SHOE-SEWING MACHINE

Application filed May 26, 1926. Serial No. 111,861.

This invention relates to shoe sewing machines and especially, although not exclusively, to machines of the type shown and described in an application for Letters Patent filed by James H. Reed, March 10, 1922, Serial No. 542,666. A machine of this type is adapted to sew a through-and-through lock stitch seam through the insole, outsole and upper of a shoe, and includes a straight hooked needle and a shuttle supplying a shuttle thread at the upper side of the work, while at the under side of the work is a work supporting horn provided with a looper or whirl which supplies a cop or needle thread, together with take-up and stitch setting mechanism to draw the needle loop over the shuttle and set the stitch.

The present invention relates particularly to the horn and certain associated parts, particularly the take-up and stitch setting mechanism. The invention has for an object to provide a simple and compact mechanism wherein a single thread engaging member performs the functions of both a stitch-forming take-up and a stitch setter, the arrangement being such as to avoid cramping of the parts, and said member engaging the thread relatively close to the stitch-forming point. Another object of the invention is to provide a construction and arrangement of parts wherein the needle or cop thread may receive an application of "hot wax" or wax which is softened by heat as distinguished from solvents, which type of wax has been found to be greatly superior to a wax solution, but which it has not usually been convenient to use in machine sewing due to its tendency to harden between the point of application and the stitch forming point. In carrying out the latter object, a heated wax pot is provided in the horn, and therefore relatively close to the stitch-forming point (the use of a single take-up member in the horn permitting this arrangement), while said horn is also provided with heating means to prevent cooling and hardening of the wax during the passage of the thread through the horn from the wax pot to the stitch forming instrumentalities.

The foregoing and other objects of the invention together with means whereby the lat-

ter may be carried into effect will best be understood from the following description of one form or embodiment thereof illustrated in the accompanying drawings. It will be understood, however, that the particular construction described and shown has been chosen for illustrative purposes merely, and that said invention, as defined by the claims hereunto appended, may be otherwise embodied without departure from the spirit and scope thereof.

In said drawings:

Fig. 1 is a side elevation, partly in section, of substantially the complete machine.

Fig. 2 is a front elevation of the lower portion of the horn and certain associated parts, the horn base and wax pot being shown in section.

Fig. 3 is a horizontal section taken substantially on line 3—3, Fig. 2.

Figs. 4 and 5 are enlarged detail sections taken on the lines 4—4 and 5—5, respectively, Fig. 2.

Figs. 6 and 7 are sections on the lines 6—6 and 7—7, respectively, Fig. 2.

In the embodiment of the invention shown, the frame of the machine comprises a base 15 carrying the work supporting horn 16 and from which rises a standard 17 carrying at its top the framework 18 of the head. The horn 16 is of a size and shape to render it capable of being inserted into the toe of a shoe and includes upper and lower angularly disposed portions D and E rigidly connected by an intermediate elbow F. Said horn is provided with a journal portion 20 rotatably mounted in a bearing 19 secured to the front of the base 15 at the top of the latter, the arrangement being such as to permit said horn to be turned as the sewing progresses. The needle 21, which is above the work A, is straight and is formed adjacent its pointed lower end with an open, loop-engaging hook, said needle being carried by a needle bar 22 guided for rectilinear reciprocating movement in the head 18. Within the tip of the horn 16, and therefore below the work, or at the opposite side thereof from the needle 21, is a whirl 23 which is rotatably mounted in said horn and is provided with an eccentric

2
opening through which the cop or needle thread C passes and with an axial opening to receive the point of the needle when the latter descends to penetrate the work, whereby said whirl operates to form a loop about the 5 needle immediately above the hook of the latter. Thereafter, as the needle rises, the loop so formed is drawn upwardly through the work. Above the work, or at the same 10 side thereof as the needle, is an oscillating discoidal shuttle 26 carrying a shuttle thread, said shuttle having a hook or beak adapted, when the needle rises, to remove the loop of needle thread from the needle hook and pass it about the shuttle and shuttle thread. The 15 machine also includes, below the work, a combined takeup and stitch setter 28 acting on the needle thread C to draw the needle loop over the shuttle and down upon the work, thereby completing the formation of the 20 stitch, and thereafter to set the latter by drawing the thread locks into the material. The needle thread is held for the action of the take-up 28 by a thread clamp 34 and is drawn 25 from the supply in measured quantities for each stitch by a combined pull-off and thread measuring device 35. Said thread is also held for the action of the pull-off 35 by a second thread clamp 36. The thread clamps 30 34 and 36 and pull-off 35 are operated by mechanism generally indicated at 37, said mechanism being preferably of the type more fully described in another application filed May 26, 1926, Serial No. 111,859.

35 The needle bar 22 and shuttle 26 are actuated through suitable connections not shown in detail, from a horizontally disposed main or power shaft 38 journalled in the head 18 and receiving power from any suitable source 40 through a pulley 39 loosely mounted thereon and connected therewith by means of a clutch 40 operated through suitable connections by a treadle lever 41 at the base of the machine. Connected, as by spiral gearing 45 42, with the shaft 38 is a vertical shaft 43 which extends downwardly along or through the standard 17, and is journaled at its lower end in a bracket 44 on the base 15.

The whirl 23 is operated by mechanism 50 which as herein shown is of the type more fully disclosed in another application filed May 26, 1926, Serial No. 111,860, and includes angularly disposed shafts 46 and 47 in the horn 16, said shafts being connected 55 with each other by gearing 48, the shaft 46 being suitably geared to the whirl 23, and the shaft 47 being connected by gearing 50 with a hollow vertical shaft 51 which extends 60 axially through the journal portion 20 of the horn. The shaft 51 is connected by gearing 53 with one end of a horizontal shaft 54 journalled in bearings on the base 15, connected 65 at its opposite end by gearing 55 with the vertical shaft 43, and carrying cams 24 and

25 for operating the thread measuring and clamping mechanism 37.

During the formation and setting of each stitch, the work A is clamped upon the horn 16 by a pressure foot 56 carried by a presser foot bar 57 which is normally pressed downwardly by a spring 31 and is periodically raised, to permit feeding of the work by instrumentalities generally indicated at 29, by means of a bell-crank lever 58 actuated by a cam on the main shaft 38. The presser foot 56 may also be manually raised to permit removal and insertion of the work by a lever 59 engaging the presser foot bar 57 and connected by a link 60 with a second lever 61 connected by a link 62 with a treadle lever 63 at the base of the machine. The presser foot bar 57 is connected by a lever 32 and link 33 with the thread measuring mechanism whereby the latter is automatically controlled in accordance with the thickness of the work.

The needle or cop thread C passes from the source of supply, not shown, through the thread measuring and clamping mechanism 34, 35, 36, thence through a tube 73 extending axially through the shaft 51 and supported at its lower end by a bracket 52 on the base 15. From the tube 73 the thread C passes through the wax pot, hereinafter described, thence about a guide roller 64 adjacent the bottom of the lower portion E of the horn, thence about a pair of guide rollers 65 located adjacent the elbow F of the horn, and thence to the whirl 23. The combined take-up and stitch setter 28 comprises a roller 66 which engages the thread C between the guide rollers 65 and is connected by a rod or link 67 with the free end of a lever 68 housed within a hollow base portion 69 of the horn, said base portion being located between the journal portion 20 and the lower portion E of the horn proper. The opposite end of the lever 68 is pivoted at 70 to a bracket 71 having a cylindrical stem portion 90 which passes axially through the journal portion 20 of the horn and in which the shaft 51 is journalled, said stem portion having a reduced lower end 91 below said journal portion. The stem portion 90 of the bracket 71 may be turned in the journal portion 20 of the horn to adjust the lever 68 into position to cooperate with the link 67 without cramping, and may be secured in adjusted position by means of a clamp 92 engaging the head of the bracket and a clamping ring 93 secured by screws 94 to the lower end of the journal portion 20 and engaging the shoulder formed by the reduced end 91.

Intermediate its ends the lever 68 is connected by a link 72 to a slide 74 guided in the stem portion 90 of the bracket 71 and having an annular head 75 surrounding and disposed coaxially with the reduced lower end 91 of said stem portion. The head 75 is formed with an annular groove 76 which receives a

stud 77 on the end of a lever 78 pivoted at 79 to the base 15 and having at its opposite end a roller or cam follower 80 engaging a path in the periphery of a cam 81 on the vertical shaft 43.

The end of the rod or link 67 is bifurcated to receive the roller 66, and the latter is mounted between the bifurcations upon a stud 82 (Fig. 5) the ends of which are extended to engage fixed guides 83 in the horn, whereby the roller 66 is directly and continuously guided for rectilinear movement immediately adjacent the thread throughout the thread deflecting movement thereof, so as to avoid cramping of the parts notwithstanding the pivotal mounting of the lever 68.

The form of the cam 81 is such that after the shuttle has been passed through the needle loop, the takeup 28 is operated to pull said 20 needle loop over the shuttle and down substantially to the work, this operation being a relatively long and slow one, and is thereafter further actuated to give the thread a short, sharp jerk, corresponding to the snap given 25 to the thread in hand sewing, in order to pull the thread locks into the material and set the stitch. To this end, the path in said cam includes a dwell *a*, a relatively long, gradual incline *b*, and a relatively short, steep offset *c*.
 30 Carried by the hollow base portion 69 of the horn is a wax pot 84 adapted to contain wax which is kept in hot, fluid condition by a suitable heating device, preferably an electric heater 85. The needle thread C, after 35 leaving the tube 73, passes through a guide 86 secured to the bottom of the lower portion E of the horn, thence through an opening in the cover 87 of the wax pot 84, thence through openings in a guide 88 within the wax pot, 40 thence through another opening in the cover 87, and thence again through the guide 86 to the guide roller 64. During its passage about the guide 88 in the wax pot, the thread C receives a coating of hot fluid wax. Since 45 the wax pot is located in the horn and thereafter relatively close to the stitch forming point, this coating of wax remains soft until the thread is used in the formation of stitches, but in order to prevent any cooling or hardening thereof, the portion of the horn through 50 which the thread passes from the wax pot to the stitch forming instrumentalities is preferably heated, which may conveniently be done by suitably disposed electric heating units 55 located between the base and the whirl, and one of which is shown at 89.

Having thus described my invention, I claim:

1. In a lock-stitch shoe sewing machine, in 60 combination, a needle, a shuttle, a horn, a whirl adapted to form a loop of thread about the needle, a single takeup engaging said thread, and actuating means for said takeup adapted to impart thereto first a relatively 65 long slow movement to draw the needle loop

over the shuttle and down upon the work and thereafter a relatively short quick movement to draw the thread locks into the work and set the stitch.

2. In a shoe sewing machine, a takeup including a link, a thread engaging roller, a stud carried by said link and on which said roller is rotatably mounted, said stud having projecting ends, and a pair of fixed guides engaged by the projecting ends of said stud. 70

3. In a shoe sewing machine, in combination, a frame, a horn having journal portion rotatably mounted in said frame, a takeup in said horn, a bracket having a stem portion disposed coaxial with said journal portion and mounted to turn therein, means for securing said bracket in adjusted position, and means for operating said takeup including parts carried by said bracket. 80

In testimony whereof I affix my signature. 85
 OSCAR L. LAWSON.
